UNITED STATES PATENT OFFICE.

MAX AUERBACH, OF BREMEN, GERMANY, ASSIGNOR TO HERMAN BLAUPOT TEN CATE,
OF WASSENAAR, NEAR THE HAGUE, NETHERLANDS.

SHUTTLE-CHANGE MECHANISM FOR LOOMS.

1,307,334.

Specification of Letters Patent. Patented June 24, 1919.

Application filed May 18, 1916. Serial No. 98,434.

To all whom it may concern:

Be it known that I, MAX AUERBACH, a subject of the Russian Emperor, and residing at Bremen, Germany, have invented certain new and useful Improvements in 5 Shuttle-Change Mechanism for Looms, of which the following is a specification.

Shuttle change mechanisms for looms have been proposed wherein the empty 10 shuttle is thrown out by a spring loaded swivel trap or wall of the shuttle box on the withdrawing of a catch or the like which holds the said trap or wall in its closed position. In such shuttle change mechanisms 15 the withdrawing of the catch is generally effected mechanically or electrically by a contact or a feeler lever which is operated on the shuttle, which is to be replaced, being wound off. Owing to this construction 20 20 the shuttle box trap is released, and consequently the shuttle replaced, only after the shuttle has been exhausted. Now it is important that the shuttle be also automatically replaced on the breakage of the weft, 25 as only in this manner the absolutely automatic working of the loom is insured on the shuttle being exhausted as well as on breakage of the weft, without any manual assistance being required.

30 To meet these requirements the present invention provides means for controlling the release of the shuttle box trap by the weft controlling member. As is well known, a weft controlling member is actuated as soon 35 as the weft loses its tension, *i. e.* as soon as it breaks or is wound off; if therefore the shuttle box trap is controlled by the weft controlling member it is clear that the shuttle is replaced as well when it is exhausted 40 as on the breakage of a weft.

The drawing herewith shows one embodiment of the invention.

Figure 1 is a plan view of my improved shuttle change mechanism.

45 Fig. 2 is an end elevation of the same partly in section.

In this embodiment the trap referred to above is constituted by a pivoted shuttle box rear wall on the lines as indicated by 50 the German specification No. 275,568.

According to the present invention the spring loaded shuttle box rear wall 5, which is kept in its closed position by a catch 9 or the like, is to be released by the weft controlling member not only when the shuttle

is exhausted, but also on the breakage of the weft.

For this purpose the catch 9 is fixed on a shaft 2 which is rotatably mounted in front of the lathe 1, in such a manner, that a rotation of the shaft 2 causes the catch 9 to descend and the shuttle box rear wall to be released. In order that the shaft 2 may be rotated on the breakage of the weft or on the shuttle being reeled off, the weft controlling member 3 which, being pivoted at 4, is lifted by the tight weft on every stroke of the lathe in a manner well known, is fixed to a link 6, which in turn is connected to a lever 8 pivoted upon a pin or stud 7. To 70 the lever 8 is fixed a rod 10 provided at its end with a catch or hook 11. The catch 11 on the rod 10 is freely located behind the nose 13 on the shaft 2. If however the lever 8 is rotated about the pin or stud 7 in the 75 direction of the arrow, this rotation being initiated by the weft controlling fork on the breakage of the weft in the manner as fully described above, the catch 11 engages the nose 13 thus imparting a rotation to the 80 shaft 2, by which the catch 9 on the shaft 2 is given a downward movement, thus releasing the swiveling shuttle box trap. As long as the weft is tight and so engages the 85 controlling member (fork) 3 on the forward stroke of the lathe, the said fork is tilted and the system 6, 8, 10, 11 and 13 remains in its relative position, so that the shaft 2 is not rotated. As soon, however, as the 90 weft breaks or is wound off, and consequently loses its tension, the fork 3 is no longer tilted on the forward stroke of the lathe, so that its hook 14 (Fig. 2) engages a lug 15 of the toothed segment 19 which receives an oscillatory motion through the 95 cam gear 16, 17, 18. This causes the fork 3 to be drawn backward by the toothed segment 19 in the direction of the arrow 20, so that the rod 6 forces the lever 8 in the direction of the arrow 12 and the hook 11 engages 100 the hook 13, rotary movement being thereby transmitted to the shaft 2, which turns the catch 9 and releases the shuttle box rear wall.

Having now particularly described and 105 ascertained the nature of my said invention and in what manner the same is to be performed, I declare that what I claim is:

1. In a loom, the combination of a shuttlebox having a pivotally mounted rear wall, 110

a member tending to impart a swiveling motion to said rear wall, a pawl for holding said rear wall in position substantially parallel with the shuttle-box front wall against the action of said member, a weft-fork adapted to be actuated on the failure of a weft across the grid, a breast-beam, a lever connected with the weft-fork and pivotally mounted on said breast-beam, and a mechanism including a catch for transmitting the motion of said lever to said pawl.

10 2. In a loom, the combination of a shuttle-box having a pivotally mounted rear wall, a spring tending to impart a swiveling motion to said rear wall, a pawl for holding said rear wall in a position substantially parallel to the shuttle-box front wall

against the action of said spring, a weft-fork adapted to be actuated on the failure of a weft across the grid, a breast-beam, a lever 20 connected with the weft-fork and pivotally mounted on said breast-beam, a rod connected with said lever, a projection on said rod, a shaft mounted along the lay-beam and connected with said pawl, and a projection 25 on said shaft adapted to coact with the said projection on the said rod.

In testimony whereof I have affixed hereunto my signature in presence of two witnesses.

MAX AUERBACH.

Witnesses.
